UNITED STATES PATENT OFFICE

1,922,120

EXPANSION SHEATH FOR WOOD-SPIKES

Richard Brosig, Bad Charlottenbrunn, Germany

Application November 3, 1932, Serial No. 641,059,
and in Germany October 5, 1931

4 Claims. (Cl. 85—2.4)

This invention relates to a sheath for wood screw-spikes, more particularly for screw-spikes for railroad sleepers.

It is known that the screw-spikes which secure the chairs or the rails to the wooden sleepers of a railroad become gradually loosened during the course of their normal use as the wood fibres deteriorate owing to constant vibration and exposure to the weather, and when loosened the screw-spikes tend to rotate and thus become disconnected from the chairs or rails.

It has been proposed to render the holes in the sleepers fit for further service by the use of screw or insert plugs but the renovation of sleepers which are still serviceable, is limited, since such sleepers can only be re-employed with the same superstructure and gauge of track, and it is necessary to secure the screw-spikes without removing the sleepers from the track.

Further it has been proposed to insert hollow plugs constructed for example of wood into the holes in the sleepers but the walls of such hollow plugs are so fragile that upon the rotation of the screw-spikes therein, the said plugs fracture and the desired object is not attained.

Again it has been proposed to surround the screw-spike with a split metal plug, but this arrangement has proved to be impracticable inasmuch as the material is rigid and the screw-spikes of necessity become loosened after a short period of use owing to the vibrations to which the track is subjected.

According to this invention a sheath for a screw-spike is provided in the form of a tube constructed of a tough and yielding material, for example, hard paper or papier-mâché and split longitudinally so that the split edges wholly or partly overlap each other.

It is sufficient if the edges of the sheath overlap each other solely in the upper part of the said sheath leaving a gap between the said edges along the lower portion thereof. The overlapping in the upper part of the sheath is desirable in order to prevent the percolation of water into the hole in the sleeper in which the sheath is arranged to be fitted.

To enable the invention to be fully understood reference is directed to the accompanying drawing in which:—

Figure 1 is a sectional elevation of a sheath for a screw-spike constructed according to the invention and

Figure 2 is a section on the line II—II on Figure 1.

Referring to the drawing there is illustrated a sheath constructed, for example, of hard paper or papier-mâché which is split longitudinally the split edges 1 and 2 being arranged so as to overlap one another at the upper end thereof.

The sheath is formed with at least one external projection, for example, the longitudinal ribs 3 which are arranged to prevent the sheath from turning when inserted in the hole in the sleeper and the said sheath is formed with an inner and outer screw-thread 4.

The longitudinal split in the sheath facilitates the introduction thereof into the hole in the sleeper, the said sheath being constructed of a diameter such that a slight compression of the said sheath is necessary during the insertion thereof, the subsequent screwing of the screw-spike within the said sheath expanding it so that it is firmly pressed against the wall of the hole in the sleeper.

An advantage attained by the use of the material referred to above, consists in that the friction between the external screw-threads of the screw-spike and the sheath is greater than that which is possible when the known split metal tube is employed.

If the upper part of the hole in the sleeper has been deformed upon one side or excessively enlarged, the upper end of the sheath may be shaped accordingly, as shown in the drawing, to provide a reinforcement for the wood around the said hole.

What I claim and desire to secure by Letters Patent of the United States is:—

1. A sheath for railroad screw-spikes which comprises an internally and externally screw-threaded tube constructed of tough and yielding material, split longitudinally, the split edges thereof overlapping one another only for a portion of the length thereof at the upper end of the tube whereby water is prevented from percolating into the hole that receives the sheath when a screw-spike is screwed into position.

2. A sheath for railroad screw-spikes which comprises an internally and externally screw-threaded tube constructed of papier-mâché, split longitudinally, the split edges thereof overlapping one another only for a portion of the length thereof at the upper end of the tube whereby water is prevented from percolating into the hole that receives the sheath when a screw-spike is screwed into position.

3. A sheath for wood railroad screw-spikes which comprises an internally and externally screw-threaded tube constructed of tough and

yielding material, split longitudinally, the said split edges thereof overlapping one another only for a portion of the length thereof at the upper end of the tube, and wherein the tube is constructed at the upper end thereof of a diameter larger relatively than the remainder of the tube, and is provided with at least one external projection arranged in the direction of the axis of the tube.

10 4. A sheath for wood railroad screw-spikes which comprises an internally and externally

screw-threaded tube constructed of papier-mâché, split longitudinally, the said split edges thereof overlapping one another only for a portion of the length thereof at the upper end of the tube, and wherein the tube is constructed at the upper end thereof of a diameter larger relatively than the remainder of the tube, and is provided with at least one external projection arranged in the direction of the axis of the tube.
